SPRAYING MACHINE

Tracy F. Brackett, Detroit, Mich., assignor to
 General Motors Corporation, Detroit, Mich., a
 corporation of Delaware

Application April 11, 1938, Serial No. 201,233

9 Claims. (Cl. 91—45)

This invention relates to the finishing of non-planar surfaces and more particularly to apparatus for spray painting the wall panels of automobile bodies.

5 An object of the invention is to provide mechanism which will maintain substantially uniform spacing between the spray nozzle and the surface of the body as it travels along the factory conveyor system.

10 A further object of the invention is to provide cooperating camming abutments on the conveyor carriage and floor, respectively, so that as the carriage moves forward it is simultaneously shifted in proper relation to the spray equipment in compensation for the curvature of the body surface in the direction of conveyor travel.

15 Additional objects and advantages will become apparent during the course of the following specification having reference to the accompanying drawing wherein Figure 1 is a side elevation showing a body supporting carriage about to engage with the elevating mechanism; Figure 2 is a perspective view illustrating the mounting of one of the camming plates and Figure 3 is an end view showing one of the carriage abutments or cam followers in engagement with the stationary cam.

20 In the drawing the reference numeral 1 indicates the floor which supports the conveyor track 2 for guiding the wheeled carriage or conveyor dolly 3. The movement of the conveyor carriage is toward the left in Figure 1, the movement being imparted through a tow bar 4 at the front end for connection with the continuously moving conveyor chain shown at 5. This is the usual arrangement for transporting automobile bodies such as seen at 6, through the paint shop for work at succeeding stations. At each of the several roof painting stations there may be 25 located a reciprocating spray gun 7 mounted on a transverse track 8 substantially as disclosed in Patent No. 2,083,633.

25 According to conventional automobile body design, the roof panel is curved both longitudinally and transversely with the longitudinal curvature being most pronounced toward the rear of the body. The rear wall of the body can be sprayed by hand but in order to reduce the amount of hand spraying necessary and to carry machine spraying to a greater extent around the curvature than is ordinarily possible it is here proposed to compensate for the recession of the body surface by raising the work during conveyor travel so that the distance between the surface and the gun is maintained constant throughout the

30 operation for uniform coating. Such raising of the body as the rear portion comes into the spraying zone is preferably at one end only and, therefore, the carriage is tilted forward to avoid too wide a departure of the paint receiving surface from a plane which is substantially normal to the direction of spray discharge.

35 The shifting of the carriage may be accomplished by providing suitably contoured cam elements on either the carriage or the floor for engagement by a cam follower. For economy it is preferable that cam followers be mounted on the several carriages for engagement with camming devices on the floor adjacent the path of carriage travel. The cam follower may consist simply of a channeled bar 9 or the like fastened to the carriage 3 and projected beyond opposite sides thereof. At each side of the carriage is located a cam plate 10 up which the followers 9 ride during conveyor travel for shifting the curved roof surface toward the gun 7.

40 From the forward edge of the roof panel to the high point near the middle the surface is substantially flat and consequently no provision need be made for shifting the body. From the high point in the roof rearwardly the curvature recedes first to a small amount and then at a higher rate to substantially the position of the window opening in the back panel. In conformity to this curvature the cam plate is given a contour such that the follower 9 rides up a gradual slope and finally a more pronounced slope to the high point of the cam corresponding to the point at which spraying is cut off. From this intermediate high point on the cam the follower rides down the opposite end of the cam until the rear wheels of the carriage are again in engagement with the conveyor track.

45 To keep down resistance it is proposed to provide either the cam follower or the cam with suitable anti-friction devices and in the embodiment illustrated the anti-friction devices are embodied in an endless roller chain 11 surrounding the cam plate 10 for movement thereon upon engagement by the follower 9. The chain 11 is of a conventional type and may consist of a series of spaced rollers successively connected by a group of links.

50 Inasmuch as some bodies may not require elevation during roof spraying the cam plate 10 is pivotally mounted on the floor so that it can be swung down out of the path of the cam followers 9. The hinged mounting, as shown in the drawing, includes a series of spaced plates 12 bolted to the cam plate 10 and pivoted or pinned

to floor plates 13. Also bolted to the hinged plates 12 is a positioning bar 14 which engages the floor as seen in Figure 3 for holding the cam plate erect and for relieving the hinge pins 5 from some of the strain. A diagonal brace rod 15 is hinged at its upper end to the plate 16 bolted to the cam 10 and at its lower end is secured by a removable pin 17 to a floor plate 18. By removing the pin 17 the brace 15 can slide on 10 the floor as the cam plate 10 is swung down.

I claim:

1. In a surface treating system of the character described, a traveling conveyor for work whose surface to be treated slopes in the direction of conveyor travel, a surface treating appliance positioned in given relation to one portion of the slope and means to maintain a substantially uniform relation between the appliance and the work surface throughout the length of 20 the slope including work shifting mechanism constructed and arranged to shift the work in relation to the appliance in compensation for said slope.

2. In a surface treating system, a traveling 25 carriage for work whose surface to be treated is curved in the direction of carriage travel, a surface treating device positioned adjacent the path of carriage travel, a ramp having a contour substantially corresponding with said surface 30 curvature and means on the carriage to ride up said ramp as an incident to carriage travel for shifting the carriage in relation to said surface treating device.

3. In roof painting apparatus of the character 35 described, an overhead spray gun, a traveling conveyor carriage for passing a body roof under the gun, and a carriage raising ramp contoured in conformity to roof contour and constructed and arranged for engagement by the carriage to 40 lift the same for maintaining given spaced relation between the gun and the roof surface being sprayed thereby.

4. Apparatus of the character described, including an overhead applicator, a wheeled conveyor carriage for a body, means for imparting 45 continuous travel to the conveyor carriage so as to pass the body roof under said applicator, a pair of roof contoured ramps on opposite sides of conveyor carriage travel, and ramp riding 50 means carried by the conveyor to raise one end of the conveyor carriage during its travel and maintain substantially uniform distance between the applicator and traveling roof.

5. For insuring proper spraying distance in

the spray painting of a curved body roof during body travel on a conveyor system, a traveling body carriage, a downwardly directed spray gun positioned above the line of carriage travel, a pair of ramps on opposite sides of the path of carriage travel through the spraying zone and a pair of ramp engaging followers on said carriage for elevation of the carriage relative to the gun during its travel.

6. In the spray painting of a curved body 10 roof, a body conveyor system including conveyor track supporting structure, a roof spraying gun having its nozzle directed transversely to the path of conveyor travel, a traveling conveyor carriage and cooperating camming abutments on the 15 carriage and supporting structure, respectively, so constructed and arranged as to ride one on the other incident to carriage travel through the spray zone for shifting carriage position in relation to the spray gun nozzle in compensation 20 for roof curvature to maintain substantially uniform spraying distance between the curved roof surface and gun nozzle.

7. The structure of claim 6 together with anti-friction load transmitting bearings carried by at 25 least one of said camming abutments for engagement with the other camming abutment.

8. In a surface finishing system of the character described, a traveling conveyor system, a spray gun adjacent thereto, a carriage engageable with the conveyor system to carry work into the spray zone of the gun and having a cam follower, a stationary camming member having an anti-friction chain tracking thereon and being positioned in relation to the gun for engagement by the follower to direct the traveling carriage in a path predetermined in relation to the surface curvature of the work, said path of travel resulting in substantially uniform spacing between the gun and the work surface being acted 35 upon.

9. In combination with a spray gun and a traveling conveyor carriage operative to bring the work into the spray zone of said gun, of mechanism to elevate the carriage during its 45 travel through the spraying zone including a stationary cam having a raceway of preselected contour, a series of rollers engageable with said raceway, an endless succession of links connecting successive rollers and a cam follower mounted on the carriage for engagement with the chain assembly of rollers and links.
